UNITED STATES PATENT OFFICE.

THOMAS E. CLARK AND JAMES E. CLARK, OF DETROIT, MICHIGAN, ASSIGNEES TO
CONTINUOUS TRAIN CONTROL CORPORATION, OF DETROIT, MICHIGAN, A COR-
PORATION OF MICHIGAN.

RAILWAY-TRAIN-CONTROL SYSTEM.

Application filed May 9, 1925. Serial No. 29,054.

This invention relates to the control of railway trains by means of a high-frequency current propagated in or imposed on railway tracks by train controlled instrumentalities positioned along the trackway 5 co-acting with brake controlling instrumentalities on the locomotives or other controlled vehicles, and embodying current collecting devices whereby the control current produced by induction may be picked up, and its object is to provide a system of this character whereby a control current will be transmitted to the train when a section of track in advance of a train is occupied, and 10 also, whenever the current propagating means at the next train-control station in advance is inoperative.

It further relates to means for visibly indicating to a following train the occupancy 20 of the first or second track section in advance, and embodies means for causing the operation of that signal which indicates the occupancy of the track between it and the next station in advance, whenever the station in advance becomes inoperative.

In railway signal and control devices of the character hereinafter described, which embody a group of lamps of different colors at each control station, means are provided whereby current flows to these lamps only when a train approaches the lamp stand or support and the current is interrupted when the train has passed the lamp stand. In the present construction, certain of the lamp 30 circuits are made use of to determine the operation of a transformer for propagating high-frequency control current in the track rails of the section in which the train is running, and proper means responsive to electric current are provided whereby each 40 signal and transforming station influences the next station in the rear, so that, should either the signal or control mechanism fail to operate, the signal mechanism and the control mechanism will be positioned in the same manner as they would if the track between such stations were occupied.

When a section of track receives this control current and a track vehicle moves along 50 this section toward the exit end where the transformer is connected to the rails and is transmitting high-frequency current thereto, a zone or field of induced current travels just in front of the leading axle of the ve-

hicle, which field becomes stronger as the 55 vehicle approaches the connections with the transmitter. Proper receiving mechanism for this indicated current is mounted on the locomotive and a relief valve controlling the brakes is normally held closed by an electro- 60 magnetic device energized by a current source on the vehicle, the circuit between them being kept closed by devices which may be controlled by the current picked up from the rails so that when this current is picked up, the circuit to the valve-controlling mechanism is opened, which will result in the 65 brakes being set.

A forestalling key is provided to close another circuit between the current source 70 and the electro-magnetic device controlling the relief valve so that the application of the brakes may be avoided.

In the accompanying drawings, Fig. 1 is a diagram of the circuits and instrumentalities embodying the present invention. Fig. 2 is a diagram of the transformer. Figs. 3 and 4 are views, partly diagrammatic and partly sectional, of the instrumentalities to be mounted on the locomotive. 80

Similar reference characters refer to like parts throughout the several views.

The track for which the present invention is designed is divided into blocks or sections each provided at its exit end with a signal 85 and control station. The direction of traffic in Fig. 1 is supposed to be from right to left, and each signal and control station is controlled by a train, if any, occupying its block and by the station next in advance. A 90 signal stand at each station near the insulation joint between adjacent blocks, is provided with the usual green, yellow and red lamps which receive current only when the block immediately in the rear is occupied so 95 that there is no unnecessary loss of current. When such block is occupied, a red light becomes visible at its exit end when the next block in advance is occupied, a yellow light when the second block in advance is occupied, and a green light when neither is occupied. The installations may be said to be in "clear", "caution" and "danger" positions when the circuits are closed to the green, yellow and red lamps, respectively. 100

In Fig. 1, the rails are lettered 1 and 2, the insulations dividing them into blocks are lettered 3 and the lamp stands by 4. The 105

wires 5 and 6 connect the track relay 7 to the rails and current for the relay is conducted to the rails by the wires 8 and 9 from the track battery 10, a resistance 11 being employed to prevent damage to the battery when a car axle on the rails short circuits this track relay. The relay 7, while energized, holds up its armatures *a*, *b* and *c* and thereby holds open the common circuit to the signal lamps and the circuits to the train control mechanism. But when this relay 7 is de-energized by reason of its block or track section being occupied, its armatures will close these circuits so that one of the lamps and the train control mechanism will function.

Each signal installation is controlled by the signal installation next in advance to the effect that if an installation is in "danger" position, the installation next in the rear will assume "caution" position and cause the second station in the rear to assume "clear" position. No installation has any effect on the stations in advance.

The sections and their installations are lettered A, B and C in Fig. 1, and these letters are occasionally associated with the numerals designating parts. Each section has a storage battery 13 or other current source and the circuits thereto are controlled in part by a polar neutral relay 14 whose winding is connected to the installation next in advance by wires 15 and 16. Current flows to this relay 14 from the station in advance over wire 15 and back over wire 16 when "clear" conditions are to control, and flows in the opposite direction when "caution" conditions are to control, while no current flows over these wires when "danger" conditions control. The relay 14 has neutral armatures *a*, *b*, *c*, and *d*, and polar armatures *e* and *f* which retain their positions until positively moved therefrom. For convenience it will be assumed that positive current flows to relay 14 of a station over wire 15 when the installation is to be at "clear," and that this causes the armatures *e* and *f* to swing clockwise, while negative current flows over this wire 15 when the installation is to be at "caution," and these armatures swing counter-clockwise.

The relays 14 and the circuits between the stations therefore control the signals. Starting with block B, where no current is received by relay 14B, current flows from the battery 13B over wires 17 and 18, dropped armature 14^c, wires 24 and 16B to relay 14C, and wire 15B, armature 25^b of station B, wire 26, armature 7^b, wire 27, armature 14^b and wires 28 and 22 to the battery.

Relay 14C is negatively energized, and if block C were not occupied, current would flow from battery 13C over wire 17, armature 14^b, wire 27, armature 7^b, wire 26, armature 25^b and wire 15C to relay 14 of station

D (not shown) and back over wires 16C and 24, armature 14^e and wires 28 and 22 to battery 13C. The result would be a positively energized relay 14 at station D. The control of relay 25 will be explained later on. 70

Section A was clear until a train (not shown) now occupying it passed signal station B, so that the polar armatures *e* and *f* of relay 14 of this station are still in the position they assumed when positive current 75 came to this relay 14 over wire 15A. But when the train entered this block A, its relay 7 was short circuited and no current flows over wire 15A.

As there is no train in block B, there is 80 no current flowing to the lamp stand at the exit end of block B, but if there were, relay 7 of block B would be de-energized and current would flow from the battery 13B over wires 17 and 18, armature 14^a and wire 19 to red lamp R and wire 20, armature 7^e and wires 21 and 22 to the battery. If for any reason therefore, no current flows to a station over wire 15A, a red lamp will indicate 85 this fact to the train approaching that station in block B.

Station C next in the rear also has a relay 14 to which the wires 15B and 16B extend from station B. Current flows from the battery 13B over wires 17 and 18, armature 14^c, wires 24 and 16B to relay 14 of station C and then over wire 15B, armature *b* of relay 25, wire 26, armature 7^b, wire 27, armature 14^b and wires 28 and 22 to the battery. Considering the current in wire 15B as a 100 negative current to relay 14C, the polar armatures 14^e and 14^f swing counter-clockwise and current will flow from the battery of station C over wires 17 and 18, armature 14^b, wire 30, armature 14^e and wire 31 to 105 lamp Y, and thence over wire 20, armature 7^e and wires 21 and 22 back to the battery.

If block C were not occupied by train T and relay 7 of station C were energized, current would flow from the battery 13C over 110 wire 17, armature 14^b, wire 27, armature 7^b, wire 26, armature 25^b and wire 15C to relay 14D (not shown), causing its armatures *e* and *f* to swing clockwise. Current at station D would then flow from the battery 115 over wires 17 and 18, armature 14^a, wire 30, armature 14^e and wire 33 to the green lamp on the stand 4. If therefore, a block is occupied, and a train approaches from a distance, a green light will show at the exit 120 end of the third block in the rear, a yellow light at the exit end of the second block in the rear, and a red light at the exit end of the next block in the rear, as each of these blocks is occupied in turn. But should one 125 of these signal installations fail to function and no current flow to the next station in the rear, a red light will immediately show at that point and the sequence of lights toward the rear will be the same as just stated.

A high-frequency current of a predetermined wave-length is propagated in the section at whose exit end a red lamp receives current, and also in the section at whose exit end, a yellow lamp receives current, and the length of track which carries a sufficient amount of this current to affect instrumentalities on the locomotive will depend upon the character of the current impressed upon the rails. The transforming and transmitting device is diagrammatically shown in Fig. 2 and described later on, and is indicated by the circle 34 in Fig. 1, current being conducted to this transmitting device only when either of the two blocks in advance is occupied, that is, when negative current or no current passes to relay 14, and occurs only when the block belonging to that transformer is occupied, and therefore when no current passes to relay 7.

When a red light is visible at the exit end of an occupied block, battery current passes from the battery of the station adjacent said exit end over wire 17, armature 14^a, wire 35, armature 7^a and wire 36 to the transformer, and wires 37, 21 and 22 to the battery. The high-frequency current passes to the rail 1 over wires 38 and 5, and to the rail 2 over wire 39, condenser 40, wire 41, relay 42 and wires 43 and 6. The condenser 40 prevents the passage of the track current from the battery 10 at the other end of the block through the relay 42 and the transformer. The relays 7 do not respond to the high-frequency current from the transformers 34.

Relay 42 responds to this current from the transformer 34 and attracts its armature *a* which closes the circuit to the relay 25, over wires 17 and 18, dropped armature 14^e wires 24 and 16 to relay 25, wire 45, armature 42^a, wires 46 and 27, dropped armature 14^b, and wires 28 and 22. Relay 25 has a heavy core and so is energized and de-energized slowly. Relay 25 being energized, attracts its armatures *a* and *b*. As soon as the train leaves block C, relay 7C becomes energized, closing a second circuit from the battery 13C over wires 17 and 18, dropped armature 14^c, wires 24 and 16 to relay 25, wire 45, armature 25^a, wire 26, armature 7^b, wire 27, dropped armature 14^d and wires 28 and 22 to the battery.

When a yellow light is visible at the exit end of an occupied block C, as indicated at the right in Fig. 1, block B being unoccupied, battery current passes from battery 13C over wires 17 and 18, armature 14^f, wires 44 and 35, armature 7^a (dropped) and wire 36 to the transformer, and wires 37, 21 and 22 to the battery. The current from the transformer passes to the rails as before described. Block C being occupied and negative current passing to relay 14C, as before explained, causing armatures 14^e and 14^f to assume counter-clockwise positions, current

will flow from the battery 13C over wires 17 and 18, armature 14^f, wire 44 to wire 35, armature 7^a and wire 36 to the transformer and back over wires 37, 21 and 22 to the battery. The transformer being energized, high-frequency current passes to the rails.

When positive current flows over the wire 15 to a relay 14 to cause the armatures 14^e and 14^f to swing clockwise, and the block approaching the station is occupied, current will pass over the wire 33 to the green lamp, but the circuits to the transmitter will be open at armature 14^a, and no control current will pass to the rails.

The advantage of this arrangement is that while a block is unoccupied and relay 7 is energized, current flows to the relay 25 of the installation of that block over armature 7^b and relay 14 of the next installation in the rear will be energized either positively or negatively. Then when the block between these installations is occupied and relay 7 is de-energized, the circuit comprising armature 7^b is broken but the circuit to the transformer 34 is closed. If now this transformer functions properly and relay 42 is energized, the second circuit to relay 25 is closed so that current will again flow to relay 14 of the block to the rear. But should the transformer fail to function, then the second circuit to the relay 25 will not be closed and no current will flow to relay 14 of the next installation in the rear and a red light will show whenever the block in the rear is occupied. The short time between the energizations of relay 42 is not sufficient for the slow relay 25 to lose its magnetism so its armatures will remain attracted during this interval.

The transformer is more fully illustrated in Fig. 2. A dynamometer 51 receives direct battery current over the wires 36 and 37, 52 and 53 and delivers direct current of from 300 to 500 volts over the wires 54 and 55. The filament 56 of the electron tube 57 connects to the wire 37 by means of an adjustable resistance 58 and connects to the wire 36 by means of the wire 59. The wire 55 connects to the plate coil 60 and to the tuning condenser 61, the wires 64 and 65 connecting this condenser and coil 60 to the plate 66. The wire 54 connects to the grid coil 67, and that connects to the grid condenser 68 and grid leak 69 by means of the wire 70. A wire 72 connects this condenser 68 and grid leak 69 of the tube 57. An output coil 74 connects to the wires 38 and 39, which, in turn, connect to the rails as above described, the condenser 40 preventing the track relay being short-circuited by this output coil. The current delivered to the rails may be of any desired wave-length, waves of from 1500 to 6000 meters in length being feasible. No claim is made of invention in the details of this transformer and transmit-

ter and any other desired means for accomplishing the same results may be employed.

If the vehicle had but a single axle which passed into a "clear" block at whose exit end a green light showed, the generator of the station of that block would not deliver current to the track rails and therefore the relay 25 would be de-energized so that no current could pass over the wire 15 leading from that station to the next station in the rear, and would remain that way. But railway vehicles have more than one axle so that two adjacent stations are occupied as the leading axle leaves the "clear" block which results in the circuit to relay 14 of the "clear" block being opened by relay 7 of the block in advance and a red light showing in place of the green light and in the generator 34 operating during the time the vehicle or trains moves out of that clear block. This gives current to relay 42 and causes relay 25 to pick up its armatures.

The locomotive installation.

25 Mounted on the locomotive at an oblique angle to the rail just in front of the leading axle where the induced field is the strongest is a collector coil 100 which connects to a thermo-junction heater current converter 101 by means of the wires 102 and 103, an adjustable condenser 104 being connected into this circuit for tuning it to resonance with the train control current propagated in the track rails.

30 A relay 105 connects to the converter by means of wires 106 and 107 and its armature *a* is normally in engagement with its back contact to close the circuit to the relay 108 which is from the battery 109 over the wire 110 to the relay 108 and thence over wires 112 and 113, armature 108^a, wire 114, armature 105^a and wires 115 and 116 back to the battery. A solenoid 117 controls the operation of the brakes, and while energized holds the valve 118 on its seat to prevent flow of air from the pipe 119 connecting to the main air reservoir of the brake system, and the circuit for this solenoid is from the wire 110 over armature 108^a and wire 120 on one side and wires 122 and 116 on the other, so that this solenoid remains energized so long as the circuit to the relay 108 remains closed. But when the collector coil 100 picks up the proper current from the rails and causes the relay 105 to pick up its armature, the circuits to both the relay 108 and solenoid 117 will be opened and remain so until both of the fore-stalling keys 122 and 123 are depressed, one of these being mounted adjacent the engineer's and the other adjacent the fireman's station. The depression of both keys simultaneously will close an auxiliary circuit between the battery and the relay 108. An accidental closing of one key at the time the coil 100 is receiving current will therefore

have no effect on the open circuit to solenoid 117. This valve and its solenoid is usually termed an electro-pneumatic valve in this art.

The relay 105 is energized only during the short time the collector coil passes along a section of track in which the control current is propagated, after which its armature will fall to bridge the two wires 114 and 115, after which the closing of both fore-stalling keys will again cause the relay 108 to pick up its armatures and complete the circuits to itself and the solenoid 117. These keys must be held depressed during the entire time the loop 100 receives current in order to prevent the application of the brakes.

The brakes are caused to be applied by the reduction of the air in the train pipe or line 130 and so long as the solenoid 117 is energized, no interference with the control of the brakes by the train valve 131 occurs. Air normally flows from this train pipe through the branch 132 to the control valve 133 and to the storage tank 134 through the pipe 135. This tank serves to reduce the speed of application of the brakes, for the openings through which the air of the train pipe escapes may be made larger when a storage tank of this character is employed.

When the solenoid 117 is de-energized and the valve 118 moves down to close the vent passage 136, air flows through the valve body 137 and pipe 138 to the whistle 139 and to the check-valve body 140, lifting the valve 142 and passing through pipes 143, 144 and 145 to the control cylinders 146 and 147 and to the storage tank 148, which merely accumulates air and permits of delayed movements of the pistons 149 and 150.

The piston 149 moves the valve 152 to close the normal passage between the train pipe 130 and the train valve 131 so that the engineer cannot supply air to the train pipe to prevent the setting of the brakes. But he can set his valve to exhaust the train line pipe. The check valve 153 will permit this upward flow of air.

When the piston 150 is forced to the position shown in Fig. 4, it connects the small passage 154 (which is controlled by the needle valve 155 and is connected to the outside air by the vent 156) to the space above the piston 157. When the parts are as shown in Fig. 3, the air pressure on both sides of this piston 157 is the same, and the passage 154 is cut off from the space above the piston 157 by the valve 158 connected to the piston 150. But when the valve 158 permits the air above the piston 157 to escape through the vent 156, the pressure below this piston, being full train pipe pressure, will lift this piston and with it the valve 159, permitting the escape of air from the train pipe through the restricted vent 160, which results in setting the brakes. This flow will

be slow because of the tank 134 which holds air at the same initial pressure and which must also escape through the vent 156.

All this time the whistle 139 is sounding and if the engineer and fireman are both alert, each can operate his forestalling key to cause the electro-magnetic valve to close. But unless the forestalling keys are depressed, air will continue to escape from the train pipe and result in the brakes being applied.

When the control keys are depressed and the solenoid 117 energized to stop the flow of air from the pipe 119, the engineer may open his train valve 131 to permit full pressure air to flow into the train pipe which will result in the valve 152 and piston 149 being pushed back to normal position, which is rendered possible by the escape of the air in the pipes 143, 144 and 145, cylinders 146 and 147 and tank 148 through the whistle 139 and vent 136, the valve 142 being so formed as to permit a slow flow of air to the pipe 138. The new pressure in the train pipe 130 and its branch 132 also forces the valve 158 and piston 150 back to the position shown in Fig. 3.

Whenever therefore, the collector coil 100 passes along a properly energized zone where it picks up current of the proper wave length, the relay 105 will cause the valve 108 to admit high pressure air to the cylinders 146 and 147, which results in the application of the brakes unless forestalled by the proper use of the keys 122 and 123 which should be so placed that they cannot be operated by one man.

The details of construction and the arrangements and positions of the various parts may all be changed by those skilled in the art without departing from the spirit of our invention as set forth in the following claims.

We claim:

1. In a railway train control system comprising signal mechanism along the trackway for visibly indicating three different speed conditions, means for propagating or imposing high-frequency current upon the rail at the points where the minimum speed condition signal is visible, means for causing such imposing of said high-frequency current when an adjacent signal mechanism becomes inoperative, and means on a vehicle on the track and extending adjacent the trackway and tuned to respond to the wave length of said imposed current to affect instrumentalities on said vehicle.

2. In a railway train control system comprising signal mechanism along the trackway for visibly indicating three different speed conditions, means adjacent each signal mechanism for imposing high-frequency current upon the rails at points where the signal for minimum speed conditions is visi-

ble, means for causing such imposing of high-frequency current when an adjacent current imposing means becomes inoperative, and means on a vehicle on the track tuned to respond to the wave lengths of 70 said imposed current.

3. In a railway train control system, a series of successive block sections, signal mechanism for each section, means in each block section to determine the character of the signals in the next section in the rear, means adjacent each signal mechanism for transforming and imposing high-frequency current upon the rails, means controlled by the signal mechanism of the next block 80 in advance to cause such imposition of current in a block occupied by a vehicle when the block in advance is occupied, and means for affecting the same result if either the signal mechanism or the transforming mechanism of the block in advance is inoperative.

4. In a railway train control system, a series of successive block sections, signal mechanism for each section embodying a 90 battery and three signal lamps and circuits between the battery and the lamps, a polar-neutral relay controlled by current from the block in advance to select the circuit to the proper signal lamp according to the occupancy of the track in advance and also controlling the signal mechanism of the track sections in the rear, means for transforming the battery current into high-frequency current of predetermined wave length and imposing the same on the track rails, means controlled by said polar-neutral relay to cause the operation of said transformer, and a relay energized by said transformer for closing the circuit from the battery to the polar-neutral relay of the next 100 installation in the rear.

5. In a railway train control system, a series of successive block sections, a signal installation for each section embodying a 110 plurality of lamps, a signal battery and a circuit from each lamp to the battery, a polar-neutral relay controlled by currents from the block in advance and adapted to select the proper lamp circuit according to the occupancy of the track in advance, batteries connected to the track at a distance to the rear from each signal installation and track relays energized thereby and located adjacent the signal installations, armatures for the track relays to open and close the circuits to said lamps, means to transform signal battery current into high-frequency current of predetermined wave 115 length, a circuit for the transformer adapted to be opened and closed by the track relay and by the polar-neutral relay, circuits connecting the transformer to the rails and embodying a third relay, a circuit between 120 the battery and the polar-neutral relay of 125 130

- the next station in the rear, said circuit being closed and opened by said third relay as that is energized or de-energized, and a fourth relay in the circuit to the polar-neutral relay of the next installation in the rear and adapted to be energized by signal battery current received over circuits adapted to be held closed by either the third relay or the track relay.
- 10 6. In a railway train control system, the combination of an air brake system embodying a relief valve adapted to be moved to open position to cause the brakes to be set, means operated by compressed air to open said valve, a control valve and electro-magnetic means to normally hold it closed to prevent the compressed air to open the relief valve, a battery and a circuit between the battery and the electro-magnetic means, a 15 relay to hold this circuit closed, a normally closed circuit between the battery and said relay, a second relay to open the circuit to the first, a collector coil and a circuit therefor to pick up high-frequency current from the track rails, means to tune the collector coil and its circuit to the wave length of the current in the track rails, and means to transform the collected current into proper current to affect the second relay, comprising a thermo-junction heater current rectifier.
- 20 8. In a railway train control system comprising signal mechanism along the trackway for visibly indicating three different speed conditions, means adjacent each signal mechanism for imposing high-frequency current upon the rails at points where the signal for either minimum or intermediate speed conditions is visible, means for causing such imposing of high-frequency current 25 when an adjacent current imposing means becomes inoperative, and means on a vehicle on the track tuned to respond to the wave length of said imposed current.
- 25 9. In a railway train control system, a track divided into blocks, a control mechanism adjacent each block adapted to impose radio-frequency current upon the rails therefor, and means for causing such imposition of current by a control mechanism when its block and either the next or second block in advance are occupied and to prevent such imposition when the two blocks in advance are unoccupied.
- 30 7. In a railway train control system, the combination of an air brake system embodying a relief valve adapted to be moved to open position to cause the brakes to be set, means operated by compressed air to open said valve, a control valve and electro-magnetic means to normally hold it closed to prevent the compressed air to open the relief valve, a battery and a circuit between the
